UNITED STATES PATENT OFFICE.

CHRISTIAN BOUILLO, OF PAYNE, AND PHILLIP BOUILLO, OF BELLEVUE, OHIO.

FASTENER FOR RECEPTACLES.

1,114,960.

Specification of Letters Patent.

Patented Oct. 27, 1914.

Application filed April 14, 1911. Serial No. 621,082.

To all whom it may concern:

Be it known that we, CHRISTIAN BOUILLO and PHILLIP BOUILLO, citizens of the United States, residing at Payne and Bellevue, in the counties of Paulding and Huron, respectively, and State of Ohio, have invented certain new and useful Improvements in Fasteners for Receptacles, of which the following is a specification.

10 The object of this invention is to provide improved fastening means for a receptacle having a door opening from one side thereof.

15 A further object of the invention is to provide an opening device for the fastening means which is movable toward an opening in the receptacle but is prevented from moving through such opening.

20 With the foregoing and other objects in view our invention consists in such details of construction and in the arrangement and combination of parts as will be hereinafter more fully described and specifically pointed out in the appended claims.

25 In describing our invention in detail reference will be had to the accompanying drawings wherein like characters denote like or corresponding parts throughout the several views and, in which:—

30 Figure 1 is a perspective view of our invention showing it applied to a door. Fig. 2 is a perspective view showing it detached from the door and having the door of the box opened. Fig. 3 is a longitudinal sectional view of the box applied to a door with the door shut. Fig. 4 is a similar view with the door open. Fig. 5 is a vertical cross section of the box with the lid closed. Fig. 6 is a detailed view of one of the 35 latches showing the construction thereof.

35 In carrying our invention into practice we provide a box 3 of any suitable size or shape. That end of the box which is adapted to abut the door frame is provided with an aperture 6. A door which opens inward to the right as you enter, will of course necessitate having the aperture 6 at the right end of the box, but if the door opens in the other direction the aperture will be disposed at the left end of the box.

40 Through the aperture 6 access may be had to the fastening device by which the lid 7 of the box is locked in closed position. This catch can of course be of any suitable construction but that illustrated in the

drawings has been found to give satisfactory results, and is preferred. This fastening device consists of two latches 8 having inclined surfaces 9 the functions of which will be hereafter more fully understood. Said latches are pivotally connected to the brackets on the cover 7 of the box. Running longitudinally of said cover is a rod 11 which is pivotally connected to each of said latches and which has one end 12 turned slightly downward so as to engage a stud 13 formed on the cover or connected thereto which stud limits the movement of said rod as will be readily understood. The other end of said rod is formed into an eye 14, disposed adjacent to the aperture 6 so that said eye may be easily engaged by a finger inserted through said aperture the latch mechanism thus being readily operated. The end 12 of the rod 11 is normally held against the buffer 13 by means of a spring 15 connected to said rod, the other end of which spring may be connected to the spindle 16 of the handle 17 on said cover or lid.

45 The latches 8 are adapted to hook over keepers 18 connected to one of the sides of said box. When the lid 7 is being closed, the inclined faces 9 of the latches come in contact with said keepers and the latches are therefore passed back against the force of the spring 15 until said bails enter the hooked part of said latches after which the cover may be opened only in the manner before pointed out. It will be seen that this 50 form of fastening means holds the lid firmly at both ends.

55 We desire it to be understood that changes in the construction and in the arrangement and combination of parts may be resorted to without departing from the spirit of our invention, provided such changes fall within the scope of the appended claims.

60 Having thus described our invention, what we claim as new and desire to secure by Letters Patent, is:—

65 1. In a receptacle of the class described, a wall provided with an opening through which the hand may be inserted, a hinged door, a latch on said door, a keeper, said latch provided with a notch to engage said bail and with an inclined face to engage said bail to guide the latch into position so that its notch will engage the bail, an 70

actuating lever accessible through said opening pivoted to said latch, and a return spring for said lever and a stop preventing movement of said lever through said opening, substantially as described.

2. In a receptacle of the class described having a door and an opening in one of its walls, a plurality of latches pivoted on the door, keepers in said receptacle for engagement by said latches, an actuating lever pivotally connected with said latches and having an operating end accessible through

said opening, and a stop engaging the opposite end of said lever for guiding and limiting movement thereof and located to prevent movement of said lever through said opening, substantially as described.

In testimony whereof we affix our signatures in presence of two witnesses.

CHRISTIAN BOUILLON.
PHILLIP BOUILLON.
